(57) **CLAIM**

The ornamental design of the insulated jacket for a bottle or a can, as shown and described.

DESCRIPTION

FIG. 1 is a perspective view of an insulated jacket for a bottle or a can shown in a configuration for holding a bottle; FIG. 2 is a front view of the insulated jacket in the bottle holding configuration;

FIG. 3 is a rear view of the insulated jacket in the bottle holding configuration;

FIG. 4 is a left side view of the insulated jacket in the bottle holding configuration, which is a mirror image of the right side view;

FIG. 5 is a top view of the insulated jacket in the bottle holding configuration;

FIG. 6 is a bottom view of the insulated jacket in the bottle holding configuration;

FIG. 7 is a side view of the insulated jacket in the can holding configuration; and,

FIG. 8 is a top perspective view of the insulated jacket in the can holding configuration.

The can shown in broken lines is for illustrative purposes only and forms no part of the claimed design.
